CLAIM

The ornamental design for an organizer, as shown and described.

DESCRIPTION

FIG. 1 is a top left front perspective view of an organizer, with a cover of the organizer in a closed position;

FIG. 2 is a front view of the organizer of FIG. 1;

FIG. 3 is a rear view of the organizer of FIG. 1;

FIG. 4 is a left side view of the organizer of FIG. 1;

FIG. 5 is a right side view of the organizer of FIG. 1;

FIG. 6 is a top view of the organizer of FIG. 1;

FIG. 7 is a bottom view of the organizer of FIG. 1;

FIG. 8 is a top left front perspective view of the organizer of FIG. 1, with the cover of the organizer in an example open position;

FIG. 9 is a front view of the organizer of FIG. 8;

FIG. 10 is a rear view of the organizer of FIG. 8;

FIG. 11 is a left side view of the organizer of FIG. 8;

FIG. 12 is a right side view of the organizer of FIG. 8;

FIG. 13 is a top view of the organizer of FIG. 8; and,

FIG. 14 is a bottom view of the organizer of FIG. 8.

The features shown in broken lines form no part of the claimed design.

1 Claim, 14 Drawing Sheets

Related U.S. Application Data

continuation of application No. 29/673,817, filed on Dec. 18, 2018, now Pat. No. Des. 943,274.
